UNITED STATES PATENT OFFICE

92,654

DESIGN FOR AN AIRPLANE

Hall L. Hibbard, Burbank, Calif., assignor to
Lockheed Aircraft Corporation, a corporation
of California

Application April 11, 1934, Serial No. 51,380

Term of patent 14 years

To all whom it may concern:

Be it known that I, HALL L. HIBBARD, a citizen of the United States, residing at Burbank, in the county of Los Angeles and State of California, have invented a new, original, and ornamental Design for an Airplane, of which the following is a specification, reference being had to the accompanying drawings, forming part thereof.

Fig. 1 of the drawings is a plan view of an airplane embodying the new design;

Fig. 2 is a front elevation of the subject airplane, showing the same as it would appear in flight with the landing wheel retracted;

Fig. 3 is a side elevation of the airplane shown

in the other figures when the landing wheels are extended for ground engagement; while

Fig. 4 is a top perspective view of the subject airplane in flight; and

Fig. 5 is a perspective view from below showing the subject airplane in flight from a different angle when the landing wheels are in retracted position as in Fig. 2.

I claim:

The ornamental design for an airplane substantially as shown and described.

In testimony whereof, I hereunto affix my signature.

HALL L. HIBBARD.
